INVENTOR:

Jacob H. Shreiner

United States Patent Office.

JACOB H. SHREINER, OF CAMP HILL, PENNSYLVANIA.

Letters Patent No. 77,924, dated May 12, 1868.

IMPROVEMENT IN GRAIN-DRILLS.

The Schedule referred to in these Letters Patent and making part of the same.

TO ALL WHOM IT MAY CONCERN:

Be it known that I, JACOB H. SHREINER, of Camp Hill, Cumberland county, Pennsylvania, have invented a new and useful Improvement in "Grain-Drills;" and I do hereby declare the following to be a full, clear, and exact description of the same, reference being had to the accompanying drawings, making a part of these specifications, and the letters of reference marked thereon.

The nature of my invention consists in the peculiar construction, combination, and arrangement of certain portions or parts of said grain-drill, in a simple and novel manner, so that great advantages are obtained over the methods of construction now in use; as is hereinafter shown. In the drawings—

Figure 1 is a perspective view of the improvement.

Figure 3 is a vertical section of the same.

Figures 2, 4, and 5 are views of parts of the device.

In figs. 1 and 3, A represents the boot or seed-conveying pipe. It, of itself, is not a new feature, as the same is now in common use. I would also state that the style of suspending it in a gang is the same as now in use. On to the lower end of the boot A, the peculiarly-shaped seeding-foot B is attached, by the dove-tail joint formed upon the back part of the boot A, as seen at e, fig. 3. It is rigidly held in place by the bolts or rivets i i, that pass through it into the portion of cutter C that extends under it, as shown in fig. 3. Said cutter C is made, on the side next the boot A, of a conforming shape to it, and extends a suitable distance up on its front part, as shown in figs. 1 and 3. The front of cutter C terminates in a sharp edge, and is intended to assist in dividing the soil. It is made of a suitable material to resist abrasion or wear, and acts as a protector to the boot A, to a certain extent. The double mould-board or seeding-foot, B, is shod upon its front with a point or share, d, which is intended to enter into and divide the soil for the reception of the seed or grain. Said share d is rigidly fastened in place by rivets or other suitable method, and is made of material of such a degree of hardness as to resist the wearing-action of the earth. The foot B is arched in the peculiar manner shown in the drawings, for the purpose of providing a sufficient space underneath it, so that the seed or grain to be sown can be properly distributed as it is fed through the boot or pipe A. This operation is greatly facilitated by the distributor s. This device is plainly shown in figs. 3 and 4. It is made funnel-shaped, and has a flange projecting from its rear, by which it is attached to the foot B. It is rigidly secured in place by bolts or rivets. The foot B is also provided with the peculiarly-constructed grooves or hollows r r', as shown in fig. 5, the intention of which is to insure the proper covering of the seed or grain, after it is sown, by their peculiar action upon the earth or loosened mould as it passes over them. At a point, u, on the boot A, a piece projects. Said projecting part is slotted, as shown in fig. 2. It is intended for the double purpose of suspending the boot A in its proper position, and also to assist in supporting the cutting-guard E. Said cutting-guard is given the form substantially as shown in fig. 1. Its upper end is slotted, so as to embrace the projection on the boot or feed-pipe A, as seen in fig. 2. It is perforated with two or more holes through its sides, for the reception of a pin or bolt, to secure the parts together. At a proper point from the lower end of guard E, the brace or supporting-piece D is fastened, between said guard and the boot A. The end of the brace D that connects with the guard is forked or slotted, so as to embrace the said guard and hold it firmly. The other end of the brace D, that connects to the boot A, has a tongue formed upon it, that enters a hole of proper size, formed for its reception, in the upper end of cutter C, and also in boot A. Its connection in said position is secured by pins, rivets, or bolts. The lower end of the cutter-guard E is given a proper degree of curvature, as seen in fig. 1, so that its point, V, will stand a short distance in advance of the point of the share d. Said point V also projects a short distance below the base-line of the share d. The point of the cutting-guard E is in a right line with the centre of the share d. All of the parts of the foregoing-described improvement are made of suitable metal or material.

Having the several parts of the device arranged as herein set forth, and a sufficient number of them placed together to form a gang or grain-drilling machine, the manner of operation is as follows: The seed or grain being fed into the boot A by the feeding-mechanism now in common use, falls down said boot and strikes the

funnel or cone-shaped distributor *s*, by which it is scattered or distributed over the ground under it in an even and regular manner, similar but superior to the broadcast sowing by hand. The grain, after it is sown, is covered perfectly, and at a uniform depth, by the loosened mould or earth being scattered upon it immediately in the rear of the foot *B*, the peculiar-shaped grooves or corrugations *r r'* greatly facilitating its accomplishment. The point *V* of guard *E* being somewhat lower than the share *d*, clears the way by cutting off small roots, grass, and other slight obstructions, and, in regard to larger impediments, it acts as a protector to the share, obviating the danger of breakage.

The principal advantages claimed for this method of constructing grain-drills are, first, the security attained by the use of the cutting-guard *E*; second, the perfect manner in which the seed or grain is distributed or spread upon the ground by the action of the conical distributor *s*, as in the ordinary grain-drills the grain is sown in a narrow trench or furrow, with no special provision for its being covered. The seed, from its crowded position, is prevented from proper germination, and, in consequence, is wasted to a certain extent. In my improved method of sowing by the use of the conical seed-distributor *s*, the disadvantages above stated are fully and perfectly overcome, and in a simple and effectual manner.

Having given a full, clear, and exact description of my invention, and its mode of operation, and set forth its advantages, what I claim as new, of my invention, and desire to secure by Letters Patent of the United States, is—

1. The peculiar construction of the foot *B*, substantially as and for the purpose herein set forth and described.
2. The combination of the foot *B*, cutter *C*, and boot *A*, substantially as herein shown.
3. The cutter-guard *E*, substantially as and for the purpose set forth.
4. The combination and arrangement of the feed-pipe or boot *A*, cutter-guard *E*, brace *D*, cutter *C*, foot *B*, and share *d*, substantially as herein set forth and for the purpose specified.

JACOB H. SHREINER. [L. S.]
